UNITED STATES PATENT OFFICE

FRANKLIN CHATFIELD, OF MINNEAPOLIS, MINNESOTA, ASSIGNOR TO THE MUNISING-WEAR CORPORATION, OF MINNEAPOLIS, MINNESOTA, A CORPORATION OF MINNESOTA

DYEING MACHINE

Application filed May 12, 1928. Serial No. 277,170.

My invention relates to machines or attachments to machines or devices for applying a coloring, moistening or softening agent or liquid or other suitable substance to a traveling yarn, thread, or fibrous material for the purpose of intermittently spotting, moistening or softening the yarn or other material, to the end that when the yarn or thread is fashioned into a garment, a pleasing mottled, spotted or variegated effect will be produced, or the yarn or thread will be suitably moistened or softened.

The primary object of the invention is to project a suitable liquid upon a receiving element to be transferred therefrom to a traveling yarn or thread.

A further object of my invention is to provide a device, by means of which the size or area of the spots formed in the yarn or thread may be varied so that the appearance of the fabric formed from the yarn or thread may be changed.

A further object is to provide means for easily and quickly changing the space or interval between the spots on the yarn or thread.

A further object is to provide a device which will permit the spots to be spaced a uniform or regular distance apart, or a variable distance as may be desired.

A further object is to provide means for shifting the yarn or thread transversely with respect to its direction of movement so that undue wear of the spot applying elements through contact with the yarn may be prevented.

A further object is to provide a rotor adapted to be engaged and operated through contact with the yarn or thread with provision for dismounting the rotor easily and quickly to substitute one of another form or type therefor.

A further object is to provide an improved receptacle or closure in which the spot applying rotor operates, all tending to faster and better work and greater ease of adjustment and change or substitution of one part for another.

Other objects of the invention will appear from the following detailed description.

The invention consists generally of various constructions and combinations, all as hereinafter described, and particularly pointed out in the claims.

In the accompanying drawings forming part of this specification,

Figure 1 is a plan view of a dyeing attachment or machine embodying my invention;

Figure 2 is a side elevation of the attachment, the wall of the rotor container being broken away to show the position of the rotor therein;

Figure 3 is a sectional view on the line 3—3 of Figure 1;

Figure 4 is a horizontal sectional view on the line 4—4 of Figure 3;

Figure 5 is an end view partially in section showing the means for directing the yarn or thread to and from the rotor and the preferred means for imparting a movement to the yarn transverse to its direction of travel;

Figure 6 is a sectional view on the line 6—6 of Figure 1;

Figure 7 is a detailed view of one form of rotor;

Figure 8 is a side view of the same;

Figure 9 is a plan view of a modified form of rotor;

Figure 10 is a detailed sectional view of a modified form of container and the manner of mounting the rotor therein; and

Figure 11 is a vertical sectional view through the shell or container of Figure 10 with the cover in its raised position, indicated by dotted lines.

In the drawing, 2 represents a suitable cup or container having suitable brackets 3 and 4 formed preferably on the lower walls thereof and provided with holes wherein supply and return pipes 5 and 6 are mounted. These pipes are of suitable size, pipe 5 being connected with a suitable source of dye supply or other liquid to be used and communicating through a duct 7 with a nozzle 8 through which the dye or other coloring agent or liquid may be discharged into the chamber 9 within the container. Any suitable means not shown may be provided for delivering the dye or other liquid to the pipe 5, and preferably this dye will be under pressure, 100

the nozzle 9 having a small discharge orifice 10 through which the dye is projected in a fine stream into the chamber 9. The excess dye or other liquid not absorbed within the chamber 9 passes by gravity through the port 11 back to the return pipe 6 to be conducted to some suitable point.

This device may be used in connection with machines of different types as an attachment therefor, or may be built into the machine itself, the location being immaterial as far as the operation of the device is concerned.

I have shown a lug 12 formed on the case of the container and adapted to receive a shaft 13 as a convenient means of supporting the device. Arms 14 are formed on the base of the container, and a rod 15 is secured to said arms. A carrier arm 17 having a sleeve 16 is mounted on the rod 15. A spring catch 18 is mounted in one of the arms 14 cooperating with a socket in the end of the sleeve 16 for normally holding the carrier arm in its closed position. This arm is adapted to overhang the open top of the container 2 and is provided with a hub 19 which depends within the chamber 9 and has a flanged portion 20 against which a cover plate 21 is seated and secured to the carrier arm by suitable means such as screws 22. A spindle 23 fits within a bore in the hub 19 and has an annular groove 24 adapted to receive a spring pressed pin 25 by means of which the spindle is normally held within the bore in the hub, but may be readily pulled therefrom, the spring pressed pin sliding on the walls of the groove and permitting freedom of withdrawal of the spindle for its re-insertion into the bore in the hub. The cover plate has preferably a series of holes 21 which admit air into the container and prevent the rotor from forming air currents or eddies therein. The spindle has a head 26 at its lower end and a hub 27 is loosely seated on said head and adapted to revolve on the spindle 23. A series of spoke-like members 28 radiate from each end of the hub 27 and these members preferably have eyes 30 formed in their outer ends. If the spoke members are made of wire, a suitable material for the purpose, the outer ends are bent and the eyes easily and quickly formed therein. The spoke members, as shown in Figure 7, are a uniform distance apart and with the supporting hub form the frame of the rotor that is carried by and rotates freely on the spindle 23.

Between the opposite spoke members I provide the dye receiving elements 31. These may be of fibrous material with their ends supported in the eyes of the spoke members and of soft yielding texture adapted to absorb the dye rapidly and a considerable quantity of it, or they may be of a harder nature and less pervious of the dye, depending upon the quantity of dye the operator wishes to apply to the yarn or thread and the diameter

or gage of these dye applying elements may be varied according to the area or size of the spots the operator wishes to form on the yarn or thread. If the operator only wishes to form small spots on the yarn or thread, then he may use a dye receiving element of small gage, or one that has a comparatively hard surface such as silk cord or thread, while on the other hand, if he wishes to increase the area of the spots, then he will use a soft dye receiving element or one that is comparatively large in cross section.

For convenience, the user of the device will supply himself with a number of rotors, each one equipped with dye receiving elements of varying gage or diameter or reception of the dye, and whenever desired, the supporting spindle may be pulled out of the hub, the rotor being used removed, and another one substituted therefor, all with comparatively little loss of time and labor.

I do not confine myself to the use of the fibrous dye receiving elements, as a fine braided or twisted wire may be used, the dye collecting in the little depressions between the strands and deposited therefrom upon the yarn or thread as it moves along.

The outer ends of the spoke members of the rotor are, as indicated in Figure 4, substantially opposite the nozzle opening 10, so that the dye delivered to the chamber 9 will be delivered to each receiving element as it is carried along by the revolving rotor.

Any other liquid of a suitable nature may be used instead of a dye with equally good results, the receiving element transmitting the liquid or semi-liquid agent from the intake nozzle to the yarn or thread.

The yarn indicated by reference numeral 32 comes from a suitable source of supply, not shown, and passes to a suitable spool or bobbin 33. The walls of the container 2 are provided with vertical slots 34 upon opposite sides of the rotor and the yarn is inserted into these slots partially encircling the rotor and contacting with a sufficient number of the dye receiving elements so that the traveling yarn will move the rotor at substantially the same speed and the contact of the yarn or thread with the dye carrying elements

will cause the transmission of the dye in spots to the yarn or thread, the distance between the spots being governed of course by the distance between the dye receiving elements and the size of the spots or area there-

of being regulated by the diameter or gage of the thread, cord or whatever may be used to receive the dye and deliver it to the yarn. The quantity of dye delivered to the chamber will of course be regulated to prevent waste or an undesirable or unnecessary delivery to the yarn.

The rod 15 has an eye 35 formed thereon and open on the under side as indicated in Figure 5 for the convenient insertion of the

yarn or thread as it passes out of the dye chamber, and at the opposite end of the rod 15, I prefer to provide a pivoted bar 36 also having an eye 35' opening upwardly instead of downwardly. A hub 37 is mounted to rock on the shaft 13 and is provided with a lug 38 that is connected with the bar 36 by a link 39. An arm 40 is secured to the shaft 13 and is provided with a roller 41 to ride on an eccentric 42 that is carried by a shaft 43. This mechanism causes a vertical oscillation of the bar 36 and a corresponding movement of the yarn transversely to its direction of travel. The purpose of this movement is to cause the yarn or thread to travel up and down on the dye receiving elements 31 as shown in Figure 2 and prevent undue wear of these elements which might result if the yarn touched them in approximately the same spot during the revolution of the rotor. The degree of transverse movement of the yarn with respect to the dye receiving elements may of course be changed as may seem advisable or necessary in the operation of the machine.

In Figure 9 I have shown a modified form of rotor in which the spoke-like members indicated by numeral 28^a are unequally spaced apart around the periphery of the rotor, the purpose of this being to prevent any possible regularity or uniformity in the spotting or coloring of the yarn or thread and lessen the chance or probability of a set pattern or figure being formed in the fabric made from the yarn or fibre so spotted. It will be understood of course that the number of these spoke-like members and the dye-carrying elements supported thereby, may be increased or decreased as preferred, and of course the spacing between the spoke-like members can be varied as conditions may require.

In Figure 10 I have shown a modification which consists in providing a modified form of cup or container 44 having a dye supply pipe 45 and a return 46, the former being equipped with a suitable nozzle 47 through which the dye is directed upon the dye receiving elements supported within the container. The rotor, which may correspond to those heretofore described, is arranged in an upright or vertical plane, its hub being supported by a pin 48 mounted in suitable bearings 49 provided in the container. The upper portion of the container is preferably open and may be closed by a suitable cover 50 of suitable material hinged at 51 if preferred and adapted to tilt to one side to expose the rotor and the chamber of the container. Suitable openings are provided in the cover 50 and guides 52 receive the yarn or thread that is stretched within the container over the top of the rotor which will be driven as the yarn or thread is fed through the container.

The device may be used as an attachment

for a machine or in any position where the dye spotting operation can be conveniently performed, as the yarn or thread travels from one holder to another or from one position to another. The carrier and cover of the container being raised, the yarn or thread can be conveniently inserted into slots 34 and carried partially around the rotor, contacting with a sufficient number of the dye receiving elements to insure the rotation of the rotor at a speed corresponding to the movement of the yarn. During this engagement of the yarn with the dye receiving elements, a suitable lateral movement will be imparted to the yarn so that its point of contact with the elements will be continually changing and thereby undue wear of the elements will be avoided. Whenever desired, the cover of the container may be raised, exposing the rotor, which may be easily and quickly removed from the carrier and another one substituted therefor in case it is desired to use dye receiving elements of greater cross sectional area or of different texture to obtain any desired change in the area or position of the spots on the yarn.

The device is shown for use in applying a suitable coloring agent to a traveling yarn or thread, but it will be understood from the foregoing description that I do not confine myself to such use, as a moistening or softening liquid or agent may be employed and applied to the yarn or thread in a manner corresponding to the application of the coloring agent, and any other liquid or semi-liquid substance in a suitable state, to be gathered by a receiving element and by it transmitted to the yarn or thread may be successfully handled with this apparatus, a feature of which is the delivery of the agent to the container and the receiving element and through or by the receiving element transmitted or applied to the traveling yarn or thread or other material that is moving through the container.

I claim as my invention:

1. A means for applying a coloring, moistening or softening agent to a traveling yarn or thread, comprising an element adapted to receive such agent and means supporting said element at each end only to contact its surface intermediate its ends intermittently with the traveling yarn or thread.

2. A means for applying a coloring, moistening or softening agent to a traveling yarn or thread, consisting of an element having means supporting it to contact its surface intermediate its ends intermittently with the traveling yarn or thread and means whereby the point of contact between the yarn and element will be changed.

3. A means for applying a coloring, moistening or softening agent to a traveling yarn or thread, consisting of an element having means supporting it to contact its

surface intermediate to its ends intermittently with the traveling yarn or thread, and means for shifting the yarn lengthwise of said element to change its point of contact therewith.

4. A means for applying a coloring, moistening or softening agent to a traveling yarn or thread, comprising a plurality of fibrous elements and means supporting them in spaced relation transversely of the traveling yarn, each element having an area for contact intermittently with the yarn, means for delivering a coloring, moistening or softening agent to such area and means for causing a relative movement of the yarn and elements transversely of the yarn.

5. A means for applying a coloring, moistening or softening agent to a traveling yarn or thread, comprising a plurality of elements supported only at their ends and adapted to receive such agent and arranged at intervals and having areas intermediate their ends for contact intermittently with a traveling yarn or thread.

6. A means for applying a suitable liquid agent to a traveling yarn or thread, comprising a fibrous element supported to allow its middle portion to have freedom of lateral movement adapted to collect such agent, and having an area intermediate its ends for contact intermittently with the traveling yarn or thread.

7. A means for applying a suitable liquid agent to a traveling yarn or thread, comprising a plurality of fibrous elements spaced apart and supported to allow freedom of movement of their middle portions transversely of the traveling yarn and each having an area adjacent the middle portion thereof for contact intermittently with the yarn.

8. A means for applying a liquid agent to a traveling yarn or thread, comprising a plurality of fibrous elements comparatively small in cross section and adapted to receive such agent and supported for engagement of areas intermediate their ends with the yarn, said elements as a whole being readily removable for substitution of a set of elements of greater or less diameter to vary the size of the spots on the yarn, for the purpose specified.

9. A means for applying a suitable coloring or softening agent to a traveling yarn or thread, comprising an element having a surface adapted to receive and retain temporarily such agent, means for projecting the agent upon such surface, and means supporting the ends of said element whereby the intermediate portion may contact with the yarn intermittently.

10. A rotor having elements mounted at intervals therein and extending substantially parallel with its axis of rotation and in the path of the traveling yarn or thread for contact intermittently therewith, said elements

being supported only at their ends and adapted to receive a suitable liquid agent for transmission to the yarn or thread.

11. A rotor and a plurality of dye receiving elements supported therein for contact intermittently with a traveling yarn or thread, and means for moving the yarn axially with respect to said rotor to vary the point of contact with said elements. 70

12. A rotor having a hub and members radiating in pairs therefrom with the pairs in spaced relation to each other, a plurality of liquid receiving elements supported between said members and having areas adapted for contact intermittently with a traveling yarn 75 or thread. 80

13. A rotor having a series of spoke-like members radiating therefrom and flexible coloring or softening receiving elements suspended by said spoke-like members at intervals, said elements having areas for contact intermittently with a traveling yarn or thread. 85

14. A rotor comprising oppositely arranged spoke-like members having eyes thereon, flexible liquid receiving elements engaged with said eyes and bridging the space between the opposite members, said elements having areas for contact at intervals with a traveling 90 yarn or thread. 95

15. The combination with a rotor composed of oppositely disposed members spaced apart, of elements bridging the gap at intervals between said members transversely to their direction of rotation and adapted to contact with the traveling yarn or thread, and means for applying a fluid to said elements. 100

16. A rotor comprising oppositely disposed members, and dye receiving elements connecting said members at intervals, the said rotor being adapted to be operated by a moving yarn or thread partially encircling said rotor and contacting successively with said elements, and a nozzle disposed externally and circumferentially of the periphery of said rotor for depositing a liquid upon the yarn contacting surfaces of said elements. 110

17. In a dyeing machine, a rotor, a plurality of receiving elements peripherally arranged in said rotor parallel with its axis, 115 and adapted to be engaged by a traveling yarn to operate said rotor, and a nozzle disposed externally and circumferentially of the periphery of said rotor for applying a fluid-like substance upon the yarn contacting surfaces of said elements for transmission to the yarn. 120

18. The combination with a container having a liquid receiving chamber, of a rotor mounted therein and having a plurality of liquid receiving elements for contact intermittently with a yarn or thread traveling through said chamber, said elements having portions unsupported intermediate their ends for contact with the yarn or thread and 125 130

- means for discharging a liquid into said chamber.
19. The combination with a dye container having a liquid receiving chamber, of a 5 rotor mounted therein and having a plurality of fibrous elements extending in a direction parallel substantially with the axis of rotation of said rotor and having areas for contact intermittently with a yarn or thread traveling through said chamber and means for discharging a dye upon said areas. 70
20. The combination with a container having ports in its walls to receive a traveling 10 yarn or thread and provided with a chamber, of a rotor and a carrier therefor, said rotor being positioned in the path of the traveling yarn or thread and provided with a coloring, softening or moistening receiving means for contact intermittently with the 15 yarn or thread and means for projecting a coloring agent upon said means. 75
21. The combination with a container having ports in its walls to receive a traveling 20 yarn or thread, of a rotor carrier and a rotor 80 projecting into said container, a plurality of liquid receiving elements mounted in said rotor and adapted to be engaged by the traveling yarn for operating said rotor, said elements being adapted to apply the liquid intermittently to the yarn and means for projecting the liquid into said container upon the 85 yarn contacting surfaces of said elements. 90
22. The combination with a container, and a rotor carrier and rotor removably mounted 95 thereon and projecting into said container, of a plurality of dye receiving elements supported in said rotor at intervals for contact intermittently with a yarn or thread traveling through said container, and means for 100 shifting the yarn laterally to change its point of contact with said elements. 105
23. The combination with a container and means for projecting a dye therein, of a rotor carrier and rotor supported thereby projecting 110 into said container, a plurality of dye receiving elements mounted in said rotor and each movable to a position to intersect the jet of dye, said elements being in the path of a yarn or thread traveling through said container to be engaged and operated through contact with such thread, for the purpose specified. 115
24. The combination with a container and means for projecting a liquid therein, of a 120 rotor carrier adapted to form the top of said container, a rotor removably mounted on said carrier, a series of receiving elements mounted at intervals in said rotor, said carrier being movable for access to said rotor, and said elements being in the path of a yarn or thread traveling through said container for contact with and to be actuated thereby. 125
25. The combination with a container and means for delivering a jet of liquid thereto, 130 the walls of said container having openings
- through which a traveling yarn or thread may pass, a rotor in said container and a plurality of receiving elements mounted therein for contact with the traveling yarn, and mechanism for shifting the yarn back and forth on said elements to vary its point of contact therewith. 70
26. A yarn or thread dyeing device comprising a cup like container having a dye receiving nozzle and a discharge port, a rotor in said container and a pivoted carrier therefor, said rotor being in the path of the yarn or thread passing through said container and having a plurality of dye receiving elements supported in said rotor to contact with the traveling yarn for driving said rotor, said dye receiving elements having their yarn contacting surfaces in the path of the dye discharged from said nozzle. 75
27. A device comprising a container having a delivering nozzle and an outlet port, a rotor and carrier therefor and cover for said container, a plurality of receiving elements mounted in said rotor for contact with a traveling yarn or thread passing through said container, suitable guides for the yarn or thread, one of them having a tilting movement, and a cam mechanism for actuating said tilting guide to shift the yarn on said receiving elements and change its point of contact therewith. 80
28. A container and means for moving a 135 yarn or thread therethrough, means for discharging a suitable agent in comparatively fine stream into said container and means having a yarn contacting surface upon which the agent is deposited for application to the yarn or thread. 100
29. A container and means for moving a 140 yarn or thread therethrough, means for projecting a suitable agent in substantially a liquid form under pressure into said container, means having a yarn contacting surface in the path of such agent for applying it to the yarn or thread, and means whereby such application will be intermittent. 105
30. A means for discharging a stream of liquid into a confined area, means for passing a yarn or thread through such area, and means having a yarn contacting surface in the path of the liquid stream adapted to receive and apply it to the yarn or thread. 110
31. A means for applying a coloring, moistening or softening agent to a traveling yarn or thread comprising a plurality of elements having areas for contact with a traveling yarn or thread and means for intermittently applying said agent in separate and individual charges to each of said elements. 115
32. A container and means for moving a 120 yarn or thread therethrough, means for delivering a suitable agent in substantially a liquid form to said container, a plurality of elements within said container and having areas for contact intermittently with a yarn 125

or thread moving through said container, said elements being adapted to receive said agent in separate and individual charges.

33. A container and means for moving a
5 yarn or thread therethrough, means for de-
livering a suitable agent in substantially a
liquid form to said container, a plurality of
elements mounted in said container in posi-
tion to be engaged and moved by the yarn or
10 thread passing through said container, the
contact of said elements with the yarn or
thread being intermittent and each element
being adapted to receive the agent delivered
to said container.

15 34. A container and means for moving a
yarn or thread therethrough, means for de-
livering a suitable coloring or softening agent
to said container, a plurality of elements
20 spaced apart and having means supporting
them to revolve within said container, said
elements being adapted to receive the color-
ing or softening agent and having areas inter-
mediate their ends for contact intermittently
25 with the moving yarn or thread, said con-
tainer having means for discharging the sur-
plus coloring or softening agent received by
said elements.

35. A means for applying a coloring, mois-
tening or softening agent to a traveling yarn
30 or thread comprising a plurality of elements
having areas for contact with a traveling yarn
or thread, rotating means supporting said
elements whereby they will have freedom of
oscillation under contact of the traveling yarn
35 or thread therewith and a nozzle disposed
externally and circumferentially of said
rotating means for applying said agent to
said elements.

In witness whereof, I have hereunto set
40 my hand this 7th day of May, 1928.

FRANKLIN CHATFIELD.
